United States Patent Office.

R. WARD, OF EDINBURG, INDIANA.

Letters Patent No. 79,791, dated July 7, 1868.

IMPROVED SMUT-MILL.

The Schedule referred to in these Letters Patent and making part of the same.

TO ALL WHOM IT MAY CONCERN:

Be it known that I, R. WARD, of Edinburg, in the county of Johnson, and in the State of Indiana, have invented certain new and useful Improvements in Combined Grain-Separator, Smut-Mill, and Riddle; and do hereby declare that the following is a full, clear, and exact description thereof, reference being had to the accompanying drawings, and to the letters of reference marked thereon.

The nature of my invention consists in the combination of a triple suction-separator and smut-mill with riddle, arranged in such a manner that the grain is first separated from all larger substances by passing through the riddle, and then goes through one suction-pipe into the smut-mill, where it is cleaned or scoured, passing at last through the second to the third suction-pipe, where it falls out of the mill, the dust, chaff, &c., having been blown out through the suction-pipes by the current of air communicated to them by a large fan attached to the mill.

In order to enable others skilled in the art to make and use my invention, I will now proceed to describe its construction and operation.

In the annexed drawings, forming part of this specification, A represents the frame on which the mill rests.

B B are arms fastened to the side of the mill, near its top, which arms extend beyond the mill, and to which the riddle C is suspended, by metal bands D D, in such a manner that it inclines toward the mill.

The riddle is an oblong metal vessel, the bottom of which is bent in circular shape, and with its mouth projecting over the hopper E on the side of the mill; and over this bent bottom, at a suitable distance above it, is a perforated metallic plate, a, the end of which projects over the spout b, which is fastened to the end of the riddle above its mouth, and projects beyond the side of the mill.

The hopper E opens into the first suction-chamber F, the lower end of which is over another hopper, G, placed on top of the smut-mill I.

The smut-mill is a large circular drum, with wooden top and bottom, secured together by rods, e e, and nuts, f f, and fastened to the frame A. Through the centre of the drum a shaft, c, passes, which shaft has its bearings at the lower end, below the drum in the frame A, and above the drum in the side of the hopper E, and this end of the shaft extends above the hopper, and is provided with a pin, d, on its edge, on which pin the riddle C rests, so that when the shaft revolves, this pin will shake the riddle sufficiently to prevent the grain from remaining in the riddle.

Inside of the drum, and near the top and bottom thereof, on the shaft c, are horizontal arms, H H, of sufficient length to allow the deeply-ribbed beaters K K, which are fastened perpendicularly on the side of the ends of these arms, to revolve freely near the inside of the drum, when the shaft is turned. On top of the beaters, and directly under the wooden top with the hopper G, is a perforated iron plate, g, fastened, which plate is of circular form, and of such a diameter that it will fit and revolve closely to the sides of the drum.

L is a cone or funnel-shaped perforated iron inside of beaters standing on the lower arms, and extending up the shaft.

The drum is open on the side where it connects with the chamber M, so that dust, &c., can be discharged into this chamber and drawn up into the second suction-pipe N, and the inside of the drum is lined with a scouring-surface provided with a series of oblong metal loops, h h, except on the side of the opening where it is provided with a series of slots, i i.

At the bottom of the drum is a spout, m, leading into the third suction-pipe O.

Q is a belt leading from the pulley n on the shaft c to the pulley o on the shaft p, which latter shaft runs through the centre of the drum R, and has its bearings in the frame A, at the bottom below the drum, and in a top-piece, r, on top of the drum.

This drum is open on one side to allow the air to pass out, and has in its top a round hole to admit the air from the wing S of the mill. The air is drawn from the different pipes through the wing and into the drum, and then forced out by means of a fan constructed of wings, s s, placed perpendicularly at the ends of the

ends of the horizontal arms t , which arms are fastened at the top and bottom on the shaft p , inside of the drum.

The top-piece r runs across the hole in the top of the drum, and is provided with followers and key for the end of the shaft p , and is oiled through the hole v on the side of the wing S . The current of air is regulated by the slide u , which covers the hole in the drum.

Near the top of the mill is a vertical slide, w , to equalize the current of air on the suction-pipes F and O , and the hole x , near this slide, is for the purpose of raising or lowering the same.

The slide y , on the side of the mill above the wing, serves to shut off the draught, when a strong current of air is on, to prevent the screenings from passing into the fan. The screenings pass through the chamber T , and are emptied out of the valve z as they accumulate.

In the chamber M is a partition-board, a' , to prevent the dust, &c., going with the grain into the last suction-pipe O , and it is also provided with a hole, b' , covered with wire to get air into the same.

When the grain is placed on the perforated plate a , and the machine is in motion, the pin d on the shaft c shakes the riddle, so that all larger substances, such as nails, sticks, straws, &c., fall off and out through the spout b , and the grain falls down on the riddle C and into the hopper E , which carries it into the suction-chamber F , and the air passing up through the same carries some of the dust along with it.

The grain then passes through the hopper G and top of the drum I , falling on the perforated plate g , and through the same, being then scoured and separated from all dust by the ribbed beaters K K , and the scouring-surface, with its oblong loops, h h .

The funnel L prevents the grain from falling down in the centre, but carries it outward to the beaters. The current of air produced by the motion of the arms and beaters blows the dust, &c., through the slots i i , into the chamber M , and, in connection with the air communicated through the hole b' , carries it up through the suction-pipe N .

The grain passes through the spout m into the third suction-pipe O , and falls down below the mill, and should any dust, &c., yet remain among it, the current of air will carry the same up this pipe.

The fan in the drum R being in motion at the same time, draws the air through the various passages, and carries the dust, &c., out of the mill, and the screenings down through the chamber T , where they are emptied through the valve z as they accumulate.

I am aware that the devices herein described, taken separately, are of themselves not new; but having thus fully described my invention,

What I claim, and desire to secure by Letters Patent, is—

The smut-mill, with drum L , constructed as described, with chamber M , suction-pipes N and O , and the fan in the drum R , with their various parts, all constructed, arranged, and operating substantially as and for the purposes specified.

In testimony that I claim the foregoing, I have hereunto set my hand; this 5th day of May, 1868.

R. WARD.
